CLAIM

The ornamental design for a stay-dry toilet seat thigh support pad, as shown and described.

DESCRIPTION

FIG. 1 is an enlarged perspective view of a stay-dry toilet seat thigh support pad showing my new design;

FIG. 2 is a top plan view thereof;

FIG. 3 is a front elevational view thereof; and,

FIG. 4 is a right side elevational view, the left side elevational view being a mirror image.

The broken line showing is for illustrative purposes only and forms no part of the claimed design.
